MOVABLE BUILDING COMPRISING A SHOWROOM

Robert W. Orlick, 5290 Villa-Way, Edina, Minn. 55436

Filed Oct. 27, 1969, Ser. No. 19,726

Term of patent 14 years

Int. Cl. D25—04

U.S. Cl. D13—1

FIG. 1 is a front view of the building.
FIG. 2 is a view of the side seen at the left in FIG. 1.
FIG. 3 is a view of the rear.

FIG. 4 is a top view.

The design is shown in full lines, and the fourth side is the same as in FIG. 2. The broken lines indicate that the design contemplates having a rotary device in each wing-aperture.

I claim:
The ornamental design for a movable building comprising a showroom, as shown and described.
